ABSTRACT

A ring counter having a number of series connected elements, each element having a feedback path to the preceding element and a feed-forward path to the succeeding element. For error-free operation, regardless of noise occurring at any input within the counter, each element requires $(n-2)$ feedback paths associated therewith, "n" being the number of elements within the counter.

RING-COUNTER

The present invention relates to ring-counters.

A ring counter generally comprises a number of series connected elements in a ring, each element having data storage and transfer capabilities such that when a clock signal is applied to the elements, data is shifted from one element to the next around the ring. Conventionally, one type of ring-counter element comprises a J-K flip-flop, the output nodes of which are connected to the inputs of the succeeding element. This type of counter has serious disadvantages in that noise upon a line carrying ZERO or ONE information throughout this specification, (ZERO is a disabling potential for devices in the elements) may give an erroneous input of the complementary binary level.

The present invention meets this problem by providing feed-back as well as feed-forward inputs. Thus, the output from one element is fed to the first input of the succeeding element (this constitutes the feed-forward path) and also to the second input of the preceding element (the feedback path). Each element therefore has a first input derived from the output of the preceding stage and a second input derived from the output of the succeeding stage. In a block of three elements, it is clear that the output from each element will affect the inputs of the other two by means of the feedback and feed-forward paths established. In fact, because of this interconnection scheme, the probability of noise on these paths causing an invalid condition within the counter is greatly reduced, as will hereinafter be explained.

Thus, according to the present invention, a ring-counter comprises a plurality of serially connected elements, each element having first and second data input terminals and a data output terminal, said data output terminal of each element connected to one data input terminal of the succeeding element to form a feed-forward path and said output terminal of each element further connected to one data input terminal of the preceding element to form a feedback path.

According to one embodiment of the invention said ring-counter contains (n) said elements and ($n-2$) feed-back paths — " n " being an integer - each one of said elements having a feed-back path extending from its data output terminal to a data input terminal upon each of ($n-2$) consecutive elements immediately preceding said one element.

According to further embodiments of the invention there are provided circuits for use in the ring counter of the invention.

The invention will now be described further by way of example only and with reference to the accompanying drawings, wherein:

FIG. 1 is a block-diagram of a ring-counter according to the prior art;

FIG. 2 is a block-diagram of part of a ring-counter according to the present invention;

FIG. 3 is a circuit diagram of a ring-counter element for use in a ring-counter according to one embodiment of the invention;

FIG. 4 is a block-diagram of a three-element ring-counter utilizing the elements of FIG. 3;

FIG. 5 is a circuit diagram of a ring-counter element for use in a ring-counter according to a further embodiment of the invention;

FIG. 6 is a circuit diagram of a ring-counter element for use in a ring-counter according to yet a further embodiment of the invention;

FIG. 7 is a block diagram of a three-element ring-counter utilizing the elements of FIG. 6;

FIG. 8 is a graph of potential versus time in respect of pulse potentials applied to the element of FIG. 6; and

FIGS. 9 and 10 are block-diagrams of ring-counters according to further embodiments of the invention.

Referring now to the drawings, and in particular to FIG. 1 thereof, a ring-counter according to the prior art comprises serially connected elements A, B and C, each element comprising a J-K flip-flop having outputs Q and Q, and inputs J and K. The Q output from each element is connected to the J input of the succeeding element and the Q output from each element is connected to the K input of the succeeding element, except for the pair of elements C and A, wherein the Q output of C is connected to the K input of A and the Q output of C is connected to the J input of A. Now, it will be appreciated that, since each of the elements essentially comprises a conventional J-K flip-flop, noise on any of the lines which tends to place the potential on that line at the complementary binary logic level to that at which the line should be, may cause the flip-flop associated with that line to give an invalid output. In other words, the counter may give more than one ONE level state, so that, for example, at any given time, instead of the state of the counter being 1,0,0, the state may be 1,1,0 — which is invalid.

Consider now FIG. 2, which shows elements A, B and C of a ring-counter according to the present invention. Now, it will be seen that each element only has one output Q and two inputs I₁ and I₂. The output Q of element B is connected to the input of I₁ of element C and the input I₂ of element A. The output Q of element C is connected to the output I₂ of element B and to the input I₁ of the succeeding stage (not shown). The output Q of element A is connected to the input I₁ of element B and to the input I₂ of the preceding stage (not shown). Thus the paths Q-I₁ may be called the feed-forward paths of the counter and the paths Q-I₂, the feedback paths. Now any noise on, say, the output Q of element B will occur on the input I₁ to element C and the input I₂ to element A. Thus, supposing at the time this noise occurs, the state of the counter is 1,0,0 (output Q from A = 1 and outputs Q from B and C = 0), then, if the noise on output Q of element B is such that element A will revert to a ZERO output as a result of such noise, then element C will also change state and go to a ONE output. Therefore, the condition of the counter becomes 0,0,1, which means that a valid condition still exists — i.e. only one ONE state — but the transmission from the condition 1,0,0 to 0,0,1 has been accomplished without passing through the condition 0,1,0. In other words, the shift of the ONE level around the counter has by-passed element B but, most importantly, the condition of the counter is valid. Now, with only one feed-back path per element, this unconditional validity only applies within blocks of three elements. To extend the operation so that invalidity cannot exist within blocks of more than three elements, more feed-back paths per cell are required as will hereinafter be described.

In FIG. 3, one circuit realization of an element for use in the ring-counter of the invention is shown. The

circuit comprises field-effect transistors T_1 to T_9 inclusive. The input I_1 is connected through transistor T_5 to the gate electrode of transistor T_3 . The gate electrode of T_5 and source electrode of T_3 are interconnected and connected to clock-signal supply C_L . The drain electrode of T_3 is connected to the source electrode of T_7 , the drain electrode of which is connected through load transistor T_8 to a potential supply rail V_{DD} . The gate electrode of T_7 is connected to the source electrode of transistor T_6 , the drain electrode of which is connected to the drain electrode of T_7 . The gate electrode of T_6 is connected to C_L . Also connected to the drain electrode of T_7 is the drain electrode of transistor T_1 , the source electrode of which is connected to reference ground potential. Transistor T_1 is cross-coupled with transistor T_2 , the gate electrode of T_1 being connected to the drain electrode of T_2 and the drain electrode of T_1 being connected to the gate electrode of T_2 . The source electrode of T_2 is connected to reference ground potential and the drain electrode of T_2 is connected to the V_{DD} rail through load transistor T_9 . The drain electrode of transistor T_4 is connected to the drain electrode of T_2 and the source electrode of T_4 is connected to reference ground potential. The gate electrode of T_4 is connected to input I_2 . Output nodes Q and Q' are at the drain electrodes of T_1 and T_2 . The operation of the circuit of FIG. 3 will hereinafter be described with reference to a complete ring-counter.

A ring-counter containing three of the elements of FIG. 3 is shown in block form in FIG. 4. The circuit comprises elements 10, 11 and 12 having signal inputs I_{101} , I_{102} ; I_{111} , I_{112} ; and I_{121} , I_{122} , respectively and outputs Q_{10} , Q_{11} and Q_{12} , respectively. Inputs I_{101} , I_{111} and I_{121} correspond to input I_1 of FIG. 3; inputs I_{102} , I_{112} and I_{122} correspond to input I_2 and outputs Q_{10} , Q_{11} and Q_{12} correspond to output Q . Remembering that elements 10, 11 and 12 form a ring, I_{101} is connected to Q_{12} and I_{102} is connected to Q_{11} . For element 11, I_{111} is connected to Q_{10} and I_{112} is connected to Q_{12} . For element 12, I_{121}

C_L	I_{101}	I_{102}	Q_{10}	I_{111}	I_{112}	Q_{11}	I_{121}	I_{122}	Q_{12}
0	0	1	0	0	0	1	1	0	0

is connected to Q_{11} and I_{122} is connected to Q_{10} . Thus inputs I_{101} , I_{111} and I_{121} may be called the "feed-forward" inputs of the counter and the inputs I_{102} , I_{112} and I_{122} may be called the "feed-back" inputs.

Each element is connected to the clock signal rail C_L in the manner of FIG. 3.

Consider now data flow through the counter. The logic-level convention used in the following description is that logic-level ONE is an "enabling potential for the transistors of the ring-counter elements and logic-level ZERO is a "disabling potential. Let it be assumed that at the beginning of a cycle of operation — say at time t_0 — output Q_{10} of element 10 is at ONE, Q_{11} is at ZERO and Q_{12} is at ZERO. At this time, C_L is at level ONE. In tabular form this is shown thusly:

C_L	I_{101} ($=Q_{12}$)	I_{102} ($=Q_{11}$)	Q_{10}	I_{111} ($=Q_{10}$)	I_{112} ($=Q_{12}$)	Q_{11}	I_{121} ($=Q_{11}$)	I_{122} ($=Q_{10}$)	Q_{12}
1	0	0	1	1	0	0	0	1	0

The state of each element at time t_0 will now be examined. Element 10 has $Q=1$, therefore T_1 is enabled. T_6 is also enabled, since $C_L=1$, and any charge on C_7 (the gate to substrate capacitance of T_7) is therefore discharged to reference ground potential through T_1

65

and T_6 . Input $I_{101}=0$ and T_5 is enabled due to C_L being ONE. Therefore, any charge on C_3 (the gate-to-substrate capacitance of T_3) is discharged through T_5 .

5 Considering element 11, $Q_{11}=0$. Input $I_{111}=1$ and T_5 is enabled due to C_L being ONE. Therefore charge is transferred to the gate of transistor T_3 and stored in capacitor C_3 . Since $Q_{11}=0$, T_1 is disabled. T_6 is enabled due to C_L and the gate of T_7 is therefore connected through T_6 to Q which is at level ONE. Therefore, charge is transferred to the gate of T_7 and stored in capacitor C_7 .

10 Considering element 12, $Q_{12}=0$. Input $I_{121}=0$ and T_5 is enabled. Therefore, any charge on C_3 is drained through T_5 . Since $Q_{12}=0$, T_1 is disabled, and T_6 is enabled due to C_L . Therefore, charge is transferred to the gate of T_7 and stored on capacitor C_7 .

15 At time t_1 , C_L swings to logic-level ZERO. Now, for element 10, T_6 and T_5 are both disabled and T_7 and T_3 are also disabled since there is no charge in capacitors C_7 and C_3 .

20 For element 11, T_6 and T_5 are disabled but T_7 and T_3 are enabled due to their gate capacitance charges. Therefore, Q_{11} is pulled down to ZERO level through T_7 and T_3 , disabling T_2 . Therefore, Q_{11} rises to level ONE, enabling T_1 and maintaining Q_{11} at level ZERO.

25 Now consider element 10 again. Input I_{102} has swung to level ONE ($I_{102}=Q_{11}$), thus enabling T_4 . Now Q_{10} is pulled down through T_4 to level ZERO.

30 Considering element 12, $I_{121}=Q_{11}=1$ and $I_{122}=Q_{10}=0$. The charge in capacitor C_7 enables T_7 but no enabling charge is at the gate of T_3 and T_3 is therefore disabled. 35 At t_0 , Q_{12} was ZERO and, therefore, since there is no current path established through T_7 and T_3 at time t_1 , Q_{12} remains at ONE and Q_{12} at ZERO.

Thus the condition of the counter at time t_1 is as follows:

45 At time t_2 , C_L swings to level ONE. Considering element 10, T_5 and T_6 are now enabled. Input $I_{101}=0$, therefore no charge is transferred to the gate of T_3 . $Q_{10}=0$, therefore T_1 is disabled and charge is transferred to the gate of T_7 and stored in capacitor C_7 .

50 Considering element 11, as both T_6 and T_5 are now enabled due to C_L , charge in capacitor C_7 is discharged through T_1 to reference ground potential ($Q_{11}=1$, therefore T_1 enabled) and charge in capacitor C_3 is discharged through T_5 to I_{111} which is at level ZERO.

55 Considering element 12, as $I_{121}=1$ and T_5 is enabled, charge is transferred to the gate of T_3 and stored in C_3 . Enabling charge at the gate of T_7 remains.

Thus, it will be seen that the conditions of the inputs and outputs of the elements 10, 11 and 12 remain the

same at time t_2 as at time t_1 and that the only changes which have taken place are the charging or discharging (as the case may be) of the capacitors C_7 and C_3 .

At time t_3 , C_L swings to ZERO. Considering element 10, the charge at the gate of T_7 enables T_7 but T_3 is dis-

abled as C_3 was previously discharged. Therefore, Q remains at ONE and Q at ZERO.

Considering element 12, each of T_7 and T_3 has enabling charge at the gate thereof and Q_{12} is pulled down to ZERO as $C_L=0$. Therefore, Q rises to ONE.

Now, considering element 11, $I_{112}=1$. Therefore T_4 is enabled, pulling Q_{11} down to level ZERO.

Thus the condition of the counter at time t_3 is as follows:

C_L	I_{101}	I_{102}	Q_{10}	I_{111}	I_{112}	Q_{11}	I_{121}	I_{122}	Q_{12}
0	1	0	0	0	1	0	0	0	1

At time t_4 , C_L swings to ONE. Considering element 10, I_{101} is ONE and T_5 is enabled, and, therefore, charge is transferred to and stored in C_3 . Q_{10} is ONE, T_1 is discharged and T_6 is enabled. Therefore, charge is transferred to and stored in C_7 .

Considering element 11, Q_{11} is ONE, T_1 is disabled and T_6 is enabled. Therefore, charge is transferred to and stored at C_7 . Since I_{111} is ZERO, no change occurs at the gate of T_3 .

Considering element 12, Q_{12} is ONE and, therefore, T_1 is enabled. T_6 is also enabled, and C_7 is discharged. I_{121} is ZERO and T_5 is enabled and, therefore C_3 is also discharged.

At time t_5 , C_L swings to ZERO. Considering element 10, T_6 and T_5 are both disabled and Q_{10} is therefore pulled down through T_7 and T_3 to ZERO due to charge accumulated in C_7 and C_3 , respectively, at time t_4 . Q_{10} therefore rises to ONE.

Considering element 12, $I_{122}=Q_{10}=1$. Therefore, T_4 is enabled and Q_{12} is pulled down therethrough to ZERO.

Considering element 11, $I_{111}=Q_{10}=1$ and $I_{112}=Q_{12}=0$. T_6 and T_5 are disabled and only the gate of T_7 has enabling charge thereupon — C_3 being discharged. Therefore no change occurs in the level of Q_{11} , T_2 remains enabled and Q_{11} remains at ZERO.

Thus the condition of the counter at time t_5 is as follows:

C_L	I_{101}	I_{102}	Q_{10}	I_{111}	I_{112}	Q_{11}	I_{121}	I_{122}	Q_{12}
0	0	0	1	1	0	0	0	1	0

Therefore, the counter has returned to the condition $Q_{10}, Q_{11}, Q_{12} = 1, 0, 0$.

Since T_7 is always enabled when T_3 is enabled, the loop comprising transistors T_6 and T_7 is not essential to the operation of the element. Thus, the drain electrode of T_3 can be connected directly to Q , instead of through T_7 , and T_6 and T_7 may be eliminated. This gives the circuit of FIG. 5. However it is desirable that T_6 and T_7 be present to increase the circuit reliability. Without T_6 and T_7 the ring-counter element is merely a clocked 55 combinatorial circuit. With the inclusion of these transistors the network becomes a sequential circuit whose next state depends on its own present state as well as the input. Thus a ONE can be transferred if and only if the input is ONE and the present state is ZERO.

FIG. 6 shows a ring-counter element according to a further embodiment of the invention. The element comprises cross-coupled transistors T_{10} and T_{11} , the gate-drain interconnects being effected through transistors T_{12} and T_{13} . The source electrode of T_{10} is connected to the gate electrode of T_{12} and to a pulse-potential supply rail ϕ_1 . The source electrode of T_{11} is connected to the gate electrode of T_{13} and to a pulse-

potential supply rail ϕ_2 . Transistor T_{14} is connected in parallel with transistor T_{10} and the gate electrode of T_{14} is connected to an input I_1 through a transistor T_{15} . The gate electrode of T_{15} is connected to the source electrode of T_{14} . The drain electrode of T_{10} is also connected through load transistor T_{18} to ϕ_1 , the drain and gate electrodes of T_{18} being interconnected. A transistor T_{16} is connected in parallel with transistor T_{11} and the gate of T_{16} is connected through a transistor T_{17} to

an input I_2 . The gate of T_{17} is connected to ϕ_1 . The drain electrode of T_{11} is connected through load transistor T_{19} to ϕ_2 , the gate and drain electrodes of T_{19} being interconnected. An output Q is derived from the source electrode of T_{19} . The operation of this circuit will be described with reference to a complete ring-counter.

A complete ring-counter containing three of the elements of FIG. 6 is shown in block form in FIG. 7. The counter again comprises elements 10, 11 and 12, each element having I_1 and I_2 inputs, designated I_{101} and I_{102} , respectively for element 10; I_{111} and I_{112} for element 11; and I_{121} and I_{122} for element 12. The outputs Q are respectively designated Q_{10} , Q_{11} and Q_{12} . Additionally, each element has connections to the ϕ_1 and ϕ_2 rails in the manner of FIG. 6. Thus, as may clearly be seen, the block diagram of FIG. 7 is identical to that of FIG. 4 except for the substitution of ϕ_1 and ϕ_2 connections for the C_L connections of FIG. 4.

Before describing the passage of data through the ring-counter, it will be helpful to establish a number of conditions for the circuit of FIG. 6;

A. When ϕ_1 goes to ZERO, the capacitances C_{10} , C_{14} and C_{16} are isolated from any discharge or charge path since each of T_{12} , T_{15} and T_{17} is disabled.

Therefore the state of each of T_{10} , T_{14} and T_{16} cannot change at least until ϕ_1 returns to ONE.

B. When ϕ_2 goes to ZERO, the capacitance C_{11} is iso-

lated from any discharge or charge path since T_{13} is disabled. Therefore the state of T_{11} cannot change until at least ϕ_2 returns to ONE.

C. When ϕ_1 goes to ONE, regardless of the state of T_{10} or T_{14} , Q unconditionally goes to ONE.

D. When ϕ_2 goes to ONE, regardless of the state of T_{11} or T_{16} , Q unconditionally goes to ONE.

E. Since each of transistors T_{15} and T_{17} are controlled by ϕ_1 , the inputs I_1 and I_2 only affect the states of T_{14} and T_{16} respectively when ϕ_1 is ONE.

F. When ϕ_1 goes to ONE, the charge potential at the gate of T_{10} , stored in C_{10} , becomes the same as the output Q potential.

G. When ϕ_2 goes to ONE, the charge potential at the gate of T_{11} , stored in C_{11} , becomes the same as Q potential.

H. Since the output Q from the circuit is unconditionally ONE when ϕ_2 is ONE, Q is only valid when ϕ_2 is ZERO.

Consider now passage of data through the ring-counter of FIG. 7. A plot of ϕ_1 versus time and ϕ_2 versus time is shown in the graph of FIG. 8, from which it

may be seen that the ϕ_1 and ϕ_2 pulses are non-overlapping and that there are time periods between pulses during which ϕ_1 and ϕ_2 are both ZERO.

The variables which affect the output Q level from the circuit of FIG. 6 are the states of transistors T_{10} , T_{11} , T_{14} and T_{16} as reflected by the charge levels (ZERO or ONE) in their gate-to-substrate capacitances C_{10} , C_{11} , C_{14} and C_{16} , respectively. The other factors are, of course, the conditions of ϕ_1 and ϕ_2 . These factors are shown at various time intervals $t_0 - t_{12}$ inclusive on the following chart, the condition of each element 10, 11 and 12 at each time interval being shown.

As shown, the counter commences in the condition 1, 0, 0 between times t_0 and t_2 . The counter passes through the states 0, 1, 0 (times $t_4 - t_6$) and 0, 0, 1 (times $t_8 - t_{10}$) before returning to the state 1, 0, 0 at time t_{12} .

The mechanisms of the circuit elements 10, 11, 12 during state transition from 1, 0, 0 to 0, 1, 0 will be described, the remainder of the cycle being readily understood by reference to FIG. 6 and the following chart.

and T_{16} must both be disabled, i.e., C_{11} and $C_{16} = 0$. Since $I_{101} = Q_{12} = 0$, and $\phi_1 = 1$, C_{14} must be ZERO. $Q_{10} = 1$ (condition C).

For element 11, $Q_{11} = 0$ and, therefore, $C_{10} = 0$ (condition F). $I_{112} = Q_{12} = 0$, and $\phi_1 = 1$. Therefore C_{16} must be ZERO. Since $\phi_2 = 0$ and $Q_{11} = 0$, T_{11} could be enabled or disabled, depending upon the previous state of Q_{11} . $I_{111} = Q_{10} = 1$, and, therefore, $C_{14} = 1$, since $\phi_1 = 1$. $Q_{11} = 1$ (condition C).

For element 12, $Q_{12} = 0$ and, therefore, $C_{10} = 0$ (condition F). Since $\phi_2 = 0$ and $Q_{12} = 0$, T_{11} could be enabled or disabled, depending upon the previous state of Q_{12} . $I_{122} = Q_{10} = 1$ and $\phi_1 = 1$. Therefore C_{16} must be ONE. $I_{121} = Q_{11} = 0$. Therefore, C_{14} must be ZERO. $\bar{Q}_{12} = 1$ (condition C).

At time t_1

For element 10, $\phi_1 \rightarrow 0$, and T_{10} is enabled by $C_{10} = 1$. Therefore, $\bar{Q}_{10} \rightarrow 0$. Since ϕ_1 and $\phi_2 = 0$, C_{10} , C_{11} , C_{14} and C_{16} remain at their previous states (conditions A and B). Since T_{11} and T_{16} remain disabled, Q_{10} remains at ONE.

Element	Time	ϕ_1	ϕ_2	Q	$\bar{Q}$	C_{10}	C_{11}	C_{14}	C_{16}

10				1	1	1	0	0	0
11	t_{12}	1	0	0	1	0	1	1	0
12				0	1	0	0	0	1

Referring now to the above chart, to FIGS. 6 and 7, and to the conditions A to D, inclusive, set forth above, the elements 10, 11 and 12 function as follows. Between times t_0 and t_1

For element 10, $Q_{10} = 1$ and, therefore, $C_{10} = 1$ (condition F). Since $\phi_2 = 0$ and $Q_{10} = 1$, if either of T_{11} or T_{16} were conducting, Q_{10} would be ZERO. Therefore T_{11}

and T_{16} must both be disabled, i.e., C_{11} and $C_{16} = 0$. Since $I_{101} = Q_{12} = 0$, and $\phi_1 = 1$, C_{14} must be ZERO. $Q_{10} = 1$ (condition C).

For element 11, $Q_{11} = 0$ and, therefore, $C_{10} = 0$ (condition F). Since $\phi_2 = 0$ and $Q_{11} = 0$, T_{11} could be enabled or disabled, depending upon the previous state of Q_{11} . $I_{111} = Q_{10} = 1$, and, therefore, $C_{14} = 1$, since $\phi_1 = 1$. $Q_{11} = 1$ (condition C).

For element 12, $Q_{12} = 0$ and, therefore, $C_{10} = 0$ (condition F). Since $\phi_2 = 0$ and $Q_{12} = 0$, T_{11} could be enabled or disabled, depending upon the previous state of Q_{12} . $I_{122} = Q_{10} = 1$ and $\phi_1 = 1$. Therefore C_{16} must be ONE. $I_{121} = Q_{11} = 0$. Therefore, C_{14} must be ZERO. $\bar{Q}_{12} = 1$ (condition C).

At time t_1

For element 10, $\phi_1 \rightarrow 0$, and T_{10} is enabled by $C_{10} = 1$. Therefore, $\bar{Q}_{10} \rightarrow 0$. Since ϕ_1 and $\phi_2 = 0$, C_{10} , C_{11} , C_{14} and C_{16} remain at their previous states (conditions A and B). Since T_{11} and T_{16} remain disabled, Q_{10} remains at ONE.

For element 11, $\phi_1 \rightarrow 0$, and T_{14} is enabled by $C_{14} = 1$. Therefore, $\bar{Q}_{11} \rightarrow 0$. C_{10} , C_{11} , C_{14} and C_{16} remain at their previous states, since ϕ_1 and $\phi_2 = 0$ (conditions A and B). Regardless of whether T_{11} is enabled or disabled, since $\phi_2 = 0$ and Q_{11} was previously ZERO, Q_{11} remains at ZERO.

For element 12, $\phi_1 \rightarrow 0$, and T_{10} and T_{14} are both

disabled. Therefore $\bar{Q}_{12}$ remains at ONE. C_{10} , C_{11} , C_{14} and C_{16} remain at their previous states, since ϕ_1 and $\phi_2 = 0$ (conditions A and B). Since $\phi_2 = 0$, Q_{12} remains in its previous state of ZERO.

At time t_2

For each element, $\phi_2 \rightarrow 1$, therefore, $Q = 1$ (condition D). Also, since $\phi_1 = 0$, C_{10} , C_{14} and C_{16} do not change.

For element 10, T_{10} remains enabled, therefore $\bar{Q}$ remains at ZERO. Thus, C_{11} remains at ZERO (condition G).

For element 11, T_{14} remains enabled, therefore $\bar{Q}$ remains at ZERO. Thus, $C_{11} = 0$ (condition G).

For element 12, T_{10} and T_{14} remain disabled, therefore $\bar{Q}$ remains at ONE. Thus, $C_{11} = 1$ (condition G).

At time t_3

For each element $\phi_2 \rightarrow 0$, therefore C_{10} , C_{11} , C_{14} and C_{16} retain their previous states (conditions A and B).

For element 10, T_{11} and T_{16} are both disabled, therefore Q_{10} remains at ONE. Since $\phi_1 = 0$ and Q_{10} was previously ZERO, $\bar{Q}$ remains at ZERO, regardless of T_{10} and T_{14} .

For element 11, T_{11} and T_{16} are both disabled, therefore Q_{11} remains at ONE. Since $\phi_1 = 0$ and $\bar{Q}$ was previously ZERO, $\bar{Q}$ remains at ZERO, regardless of T_{10} and T_{14} .

For element 12, T_{11} and T_{16} are both enabled. Since $\phi_2 = 0$, $Q_{12} \rightarrow 0$. Since neither T_{10} or T_{14} is enabled, $\bar{Q}$ remains in its previous state, i.e., ONE.

At time t_4

For each element, $\phi_1 \rightarrow 1$, therefore $\bar{Q} = 1$ (condition C). Since $\phi_2 = 0$, C_{11} retains its previous state.

For element 10, $I_{102} = Q_{11} = 1$. Therefore, $C_{16} \rightarrow 1$ and T_{16} is enabled and, since $\phi_2 = 0$, $Q_{10} \rightarrow 0$ (condition F).

For element 11, $I_{112} = Q_{12} = 0$. Therefore C_{16} remains at ZERO and T_{16} is disabled. Since T_{11} is disabled, Q_{11} is isolated from $\phi_2 = 0$ and remains at ONE. Also $C_{10} = 1$ (condition F).

For element 12, $I_{122} = Q_{10} = 0$. Therefore $C_{16} \rightarrow 0$. However since $\phi_2 = 0$, Q_{12} remains at ZERO regardless of the states of T_{11} and T_{16} . Also $C_{10} = 0$ (condition F).

To determine C_{14} for each element; for element 10, $I_{101} = Q_{12} = 0$, therefore $C_{14} = 0$. For element 11, $I_{111} = Q_{10} = 0$, therefore $C_{14} \rightarrow 0$. For element 12, $I_{121} = Q_{11} = 1$, therefore $C_{14} \rightarrow 1$.

At time t_5

For each element, $\phi_1 \rightarrow 0$ and ϕ_2 remains at ZERO. Therefore, the capacitances C_{10} , C_{14} , C_{16} and C_{11} cannot charge (conditions A and B). Also, I_1 and I_2 for each element cannot affect the states of Q and $\bar{Q}$ (condition E).

For element 10, $Q = 0$ and, since ϕ_2 is ZERO, Q remains at ZERO, regardless of the states of T_{11} and T_{16} . $\bar{Q} = 1$ and T_{10} and T_{14} are both disabled. Therefore, Q remains at ONE.

For element 11, $Q = 1$ and, since T_{11} and T_{16} are both disabled, Q remains at ONE. $\bar{Q} = 1$, but, since $C_{10} = 1$, T_{10} is enabled, and $Q \rightarrow 0$.

For element 12, $Q = 0$ and, since ϕ_2 is ZERO, Q remains at ZERO, regardless of the states of T_{11} and T_{16} . $\bar{Q} = 1$, but, since $C_{14} = 1$, T_{14} is enabled, and $\bar{Q} \rightarrow 0$.

At time t_6

For each element, $\phi_2 \rightarrow 1$ and ϕ_1 remains at ZERO. Therefore, the capacitances C_{10} , C_{14} and C_{16} are iso-

lated from any charge or discharge paths since T_{12} , T_{15} and T_{17} are disabled. Also, since ϕ_2 is now ONE, Q must unconditionally be ONE.

For element 10, T_{13} is enabled by $\phi_2 = 1$, and since $\bar{Q}$ is ONE, $C_{11} \rightarrow 1$. T_{14} and T_{10} are both disabled, therefore $\bar{Q}$ remains at ONE.

For element 11, T_{13} is enabled and C_{11} remains at ZERO, since $\bar{Q} = 0$. $\bar{Q}$ does not change.

For element 12, $\bar{Q}$ remains at ZERO and, since T_{13} is enabled, $C_{11} \rightarrow 0$.

At time t_7

For each element, ϕ_1 and ϕ_2 are both ZERO, therefore the states of T_{10} , T_{11} , T_{14} and T_{16} remain unchanged.

For element 10, since $\phi_2 \rightarrow 0$ and T_{11} and T_{16} are enabled, $Q \rightarrow 0$. ϕ remains at ZERO, therefore $\bar{Q}$ remains at ZERO.

For element 11, $\bar{Q}$ remains at ZERO, since $\phi_1 = 0$. T_{11} and T_{16} are both disabled, therefore Q remains at ONE.

At time t_8

For each element, ϕ_2 remains at ZERO, therefore C_{11} remains unchanged. $\phi_1 \rightarrow 1$, therefore $\bar{Q} \rightarrow 1$.

For element 10, $\phi_2 = 0$, therefore Q remains at ZERO. Since $Q = 0$, C_{10} remains at ZERO. $I_{101} = Q_{12} = 1$, therefore C_{14} remains at ONE. $I_{102} = Q_{11} = 0$, therefore $C_{16} \rightarrow 0$.

For element 11, $I_{112} = Q_{12} = 1$, therefore $C_{16} \rightarrow 1$. $I_{111} = Q_{10} = 0$, therefore C_{14} remains at ZERO. Since T_{16} is enabled, $Q_{11} = \phi_2 = 0$. Therefore $Q_{11} \rightarrow 0$. Now, since $Q_{11} = 0$, and $\phi_1 = 1$, $C_{10} = Q_{11} = 0$. Therefore $C_{10} \rightarrow 0$.

For element 12, $I_{121} = Q_{11} = 0$, therefore $C_{14} \rightarrow 0$. $I_{122} = Q_{10} = 0$, therefore C_{16} remains at ZERO.

At time t_9

For each element $\phi_1 \rightarrow 0$, ϕ_2 remains at ZERO. Therefore, the states of T_{10} , T_{11} , T_{14} and T_{16} remain the same as at time t_8 .

For element 10, since ϕ_2 is ZERO, Q_{10} remains at ZERO. Since $\phi_1 \rightarrow 0$ and T_{14} is enabled, therefore $Q_{10} \rightarrow 0$.

For element 11, since ϕ_2 is ZERO, Q_{11} remains at ZERO. Since T_{10} and T_{14} are disabled, $\bar{Q}_{11}$ remains at ONE.

For element 12, since T_{11} and T_{16} are disabled, Q_{12} remains at ONE. Since T_{10} is enabled and $\phi_1 \rightarrow 1$, $Q_{12} \rightarrow 1$.

At time t_{10}

For each element, $\phi_2 \rightarrow 1$ and ϕ_1 stays at ZERO. Therefore Q is unconditionally ONE. Since $\phi_1 = 0$, T_{10} , T_{14} and T_{16} remain unchanged.

For element 10, since $\phi_1 = 0$, $\bar{Q}_{10}$ stays at ZERO. Since T_{13} is enabled by $\phi_2 = 1$, $C_{11} \rightarrow \bar{Q}_{10} = 0$. Therefore T_{11} is disabled.

For element 11, since T_{10} and T_{14} are both disabled, $\bar{Q}_{11}$ remains at ONE. Since T_{13} is enabled by $\phi_2 = 1$, $C_{11} \rightarrow \bar{Q}_{11} = 1$. Therefore T_{11} is enabled.

For element 12, since $\phi_1 = 0$, $\bar{Q}_{12}$ remains at ZERO. Since T_{13} is enabled by $\phi_2 = 1$, $C_{11} \rightarrow \bar{Q}_{12} = 0$.

At time t_{11}

For each element, $\phi_2 \rightarrow 0$. ϕ_1 remains at ZERO. Therefore, each of C_{10} , C_{11} , C_{14} and C_{16} is unchanged. For element 10, T_{11} and T_{16} are both disabled, therefore Q_{10} remains at ONE. Since $\phi_1 = 0$, Q_{10} remains at ZERO.

For element 11, T_{11} and T_{16} are both enabled and $\phi_2 \rightarrow 0$. Therefore $Q_{11} \rightarrow 0$. Since T_{14} and T_{19} are disabled, $\bar{Q}_{11}$ remains at ONE.

For element 12, T_{11} and T_{16} are both disabled therefore Q_{12} remains at ONE. Since $\phi_1 = 0$, $\bar{Q}_{12}$ remains at ZERO.

At time t_{12}

For each element, $\phi_1 \rightarrow 1$. ϕ_2 remains at ZERO. Therefore, the state of C_{11} remains unchanged. Also, $\bar{Q}$ is unconditionally ONE.

For element 11, $I_{111} = Q_{10} = 1$, therefore, $C_{14} \rightarrow 1$. $I_{112} = Q_{12} = 0$, therefore, $C_{16} \rightarrow 0$. $\phi_2 = 0$, therefore Q_{11} remains at ZERO. Since $Q_{11} = 0$, C_{10} remains at ZERO.

For element 12, $I_{121} = Q_{11} = 0$, therefore C_{14} remains at ZERO. $I_{122} = Q_{10} = 1$, therefore $C_{16} \rightarrow 1$. Since T_{16} is enabled $\phi_2 = Q_{12} \rightarrow 0$. Since T_{12} is enabled by $\phi_1 = 1$, $Q_{12} = C_{10} \rightarrow 0$.

For element 10, $I_{101} = Q_{12} = 0$, therefore $C_{14} \rightarrow 0$. $I_{102} = Q_{11} = 0$, therefore C_{16} remains at ZERO. T_{11} remains disabled, therefore Q_{10} remains at ONE. Since $\phi_1 = 1$, T_{12} is enabled and $Q_{10} = C_{10} \rightarrow 1$.

Thus, at time t_{12} the ring-counter has gone through a complete cycle; the condition thereof once again being 1, 0, 0.

The foregoing sequence of events is shown graphically in FIG. 8, which is a graph of time (T) versus logic level (V) in respect of times t_0 to t_{12} inclusive and the logic levels of elements 10, 11, 12 and pulse trains ϕ_1 and ϕ_2 , respectively. It may be readily seen from FIG. 8 that the counter state is valid from times $t_0 - t_2$; $t_4 - t_6$; and $t_8 - t_{10}$. At time t_{12} , the sequence to events begins to repeat and, therefore, t_{12} is analogous to t_0 . It may be also be seen that the state goes valid when ϕ_1 goes to level ONE and remains valid until ϕ_2 goes to level ONE. When ϕ_2 is ONE, the counter is going through a transition between valid states, during which period, the state of the counter is invalid. Thus, the counter may only be validly read when ϕ_1 goes to level ONE and until ϕ_2 goes to ONE.

Turning now to FIG. 9, there is shown a complete ring-counter having at least five elements 10 to 14 inclusive. It has been stated herein that the unconditional validity of the ring-counter of the invention where each element has only one feedback path and one feed-forward path is limited to blocks of three elements. This may be demonstrated by considering the ring-counter shown in FIG. 9 in conjunction with the circuit exemplified in FIG. 3.

Consider firstly FIGS. 3 and 4 together. Referring back to the description of FIG. 3, at time t_0 ,

$$\begin{aligned} C_L &= 1 \\ I_{101} &= Q_{12} = I_{112} = 0 \\ I_{102} &= Q_{11} = I_{121} = 0 \\ I_{111} &= Q_{10} = I_{122} = 1 \end{aligned}$$

Now, suppose, for example, noise appears at the input I_{121} such that $I_{121} = 1$.

For element 10, I_{102} is now ONE and T_4 is therefore enabled. Q_{10} is now discharged to ground through T_4 and $Q_{10} \rightarrow 0$. Also, the charge on T_1 is drained to ground and T_1 is disabled.

For element 11, $I_{121} = Q_{11}$ and, therefore, $Q_{11} \rightarrow 1$.

For element 12, $I_{121} = Q_{11} = 1$ and $I_{122} = Q_{10} = 0$. Since C_L is ONE, T_5 and, hence, T_3 are enabled. Now, C_7 charges during the time period $t_0 - t_1$. Therefore, at time t_0 , C_7 is not yet charged, and T_7 is disabled, and charge therefore remains at the gate electrode of T_2 , maintaining T_2 in its enabled state. Therefore, Q_{12} is

pulled down to reference ground potential through T_2 , and goes to ZERO.

Thus, the state of the counter has gone from 1, 0, 0 to 0, 1, 0 when noise appears at the input I_{121} , at time t_0 .

Suppose the noise appeared towards the end of the time period $t_0 - t_1$. Now, C_7 of element 12 would be substantially fully charged and, since T_3 is enabled as explained above, the gate electrode of T_2 is discharged through T_7 and T_3 . Thus, since $I_{122} = 0$, Q_{12} goes to ONE. When $Q_{12} \rightarrow 1$, I_{101} and $I_{112} \rightarrow 1$. When I_{112} is ONE, T_4 of element 11 is enabled and Q_{11} remains at ZERO. The noise appearing at I_{121} , such that $I_{121} \rightarrow 1$, also affects I_{102} , which also goes to ONE. Now, for element 10, T_4 is enabled and Q_{10} , therefore, goes to ZERO.

Thus the counter has gone directly from the state 1, 0, 0 to 0, 0, 1 — bypassing the 0, 1, 0 state.

In fact, if the circuit is examined in the condition where noise occurs at any one of the inputs at any given point in time during data transfer through the counter, it will be seen that the state of the counter always changes to another valid state.

Now, consider FIG. 3 in conjunction with the counter of FIG. 9, wherein like elements are referenced in like manner to FIG. 4.

Assuming there are only the five elements shown in the counter of FIG. 9, at time t_0 , the counter state is 1, 0, 0, 0, 0. Therefore, considering element 12, $I_{122} = 0$ and $I_{121} = 0$ and $Q_{12} = 0$. Now, since T_1 is disabled and T_6 is enabled by $C_L = 1$, C_7 charges up to enable T_7 (see FIG. 3). Suppose noise now appears at I_{121} which raises this input to level ONE. T_5 is enabled by $C_L = 1$ and passes the ONE level input at I_{121} to the gate of T_3 , which stores charge in C_3 . At time t_1 , $C_L \rightarrow 0$ and T_3 and T_7 are both enabled by charge at their gate capacitances. Therefore, any charge at the gate capacitance of T_2 is discharged to C_L through T_3 and T_2 is disabled. Therefore, $Q_{12} \rightarrow 1$, since no change has occurred in element 13, and I_{122} therefore remains at ZERO, maintaining T_4 in its disabled state. Therefore, we have an invalid state of the counter, since Q_{10} remains at ONE, there being no feedback or feed-forward path associated therewith which is affected by the noise at I_{121} .

Upon analysis, it becomes clear that any given element only affects the preceding and succeeding elements by virtue of its feed-back and feed-forward paths. Thus, if that element is caused to change state by virtue of noise at one input thereto, the only other elements which are affected are the immediately adjacent elements. If the noise causes a ONE output from that element and a valid ONE output is already being derived from an element not adjacent thereto, then there will be two ONE outputs generated, giving an invalid condition.

By consideration of the foregoing, it will now be realized that each element must affect all of the preceding and succeeding elements in the counter by means of feed-back and feed-forward paths, if a totally error-free system is to be realized. This is shown in the ring-counter of FIG. 10, which is a five-element counter. The counter comprises elements 10 to 14 inclusive, each element having three feed-back and one feed-forward path connected to its output. The input and output to the elements are designated I and Q, respectively, in the same manner as in FIG. 9. It will be seen that by having a feed-back path to each of the other elements in the counter except one — which has a feed-forward path thereto — there are in the general case

($n-2$) feed-back paths associated with each element, wherein n is the number of elements in the counter. Thus, there are ($n-2$) feed-back inputs associated with each element and, since noise on any input must affect the condition of the element with which it is associated — independently of the condition of the other inputs to that element — the feed-back inputs are fed to the element through an OR gate OR-10; OR-11 . . . OR-14. With this arrangement, it is apparent that noise occurring anywhere in the counter, which causes the condition of an element to change, will affect the remaining elements such that only one element will give a ONE output and the counter will therefore continue to assume a valid state.

Although the ring-counter of the invention has been exemplified with reference to specific embodiments thereof utilizing field-effect transistors, it will be apparent that the concept of the invention is equally valid when the ring-counter is composed of elements using bipolar techniques, providing such elements have inputs and outputs interconnected and functioning in the manner taught herein.

Various alternatives and modifications to the embodiments disclosed herein will be readily apparent to those skilled in the art without departing from the spirit and scope of the invention as described by the disclosure and defined by the claims appended hereto.

What is claimed is:

1. A ring-counter comprising a plurality of serially connected elements, each element having first and second data input terminal means and a data output terminal means, said data output terminal means of each element connected to one data input terminal means of the succeeding element to form a feed-forward path, and said output terminal means of each element further connected to the second data input terminal means of the preceding element to form a feed-back path; " n " said elements, " n " being an integer greater than 2, each one of said elements having a feed-back path extending from its data output terminal to the second data input terminal means upon each of $n-2$ consecutive elements immediately preceding said one element.

2. The ring counter of claim 1 wherein the second data input terminal means upon each of said elements is connected to said feedback paths through an OR-gate lens, the output of each of said OR-gate means being connected to said second data input terminal means, and the inputs to each of said OR-gate means being connected to each of said feedback paths which is to be connected to the respective one said terminal.

3. A ring-counter comprising a plurality of serially connected elements, each element having first and second data input terminal means and a data output terminal means, said data output terminal means of each element connected to one data input terminal means of the succeeding element to form a feed-forward path, and said output terminal means of each element further connected to the second data input terminal means of the preceding element to form a feed-back path, each said element having first and second cross-coupled field-effect transistors, the drain electrode of said first transistor connected to the gate electrode of said second transistor and the gate electrode of said first transistor connected to the drain electrode of said second transistor;

a fifth transistor, the gate electrode of which is connected to means for connection to a pulse potential supply means;

a third transistor having its source electrode connected to said means for connection to said pulse potential supply means and its gate electrode connected through said fifth transistor to first input terminal means;

the gate electrode of said third transistor connected through capacitance means to means for connection to a reference ground potential point;

the drain electrode of said first transistor connected through first load means to means for connection to a drain-potential supply rail and the drain electrode of said second transistor connected through second load means to means for connection to said drain-potential supply rail, the source electrodes of said first and second transistors connected to means for connection to a reference ground potential point;

a fourth transistor connected in parallel with said second transistor across the source and drain electrodes thereof, said fourth transistor having its gate electrode connected to second input terminal means and capacitance means connected between the gate electrode of said fourth transistor and means for connection to a reference ground potential point;

the drain electrode of said first transistor connected to the drain electrode of said third transistor and the drain electrode of said second transistor connected to output terminal means;

said output terminal means of each said element being connected to said second input terminal means of the preceding said element in said ring-counter and also connected to said first input terminal means of the succeeding said element in said ring-counter.

4. The ring-counter of claim 3 wherein said ring-counter contains " n " said elements — " n " being an integer greater than 2 — said output terminal means of each one of said elements being connected to said second input terminal means of each of the ($n-2$) consecutive elements immediately preceding said one element.

5. The ring counter of claim 4 wherein said first and second load means comprise eighth and ninth field-effect load transistors, respectively.

6. The ring-counter of claim 4 in integrated circuit form wherein said capacitance means comprise the gate to substrate capacitances of said third and fourth transistors.

7. The ring-counter of claim 4 wherein said capacitance means comprise the gate to substrate capacitances of said third and fourth transistors and each of said first and second load means comprises a field-effect load transistor.

8. The ring-counter of claim 3 wherein said first and second load means comprise eighth and ninth field-effect load transistors, respectively.

9. The ring-counter of claim 3 in integrated circuit form wherein said capacitance means comprise the gate to substrate capacitances of said third and fourth transistors.

10. The ring-counter of claim 3 wherein said capacitance means comprise the gate to substrate capacitances of said third and fourth transistors and each of said first and second load means comprises a field-effect load transistor.

11. A ring-counter comprising a plurality of serially connected elements, each element having first and sec-

ond data input terminal means and a data output terminal means, said data output terminal means of each element connected to one data input terminal means of the succeeding element to form a feed-forward path, and said output terminal means of each element further connected to the second data input terminal means of the preceding element to form a feed-back path, each said element having first and second cross-coupled field-effect transistors, the drain electrode of said first transistor connected to the gate electrode of said second transistor and the gate electrode of said first transistor connected to the drain electrode of said second transistor;

10 fifth and sixth transistors, the gate electrodes of which are connected to means for connection to a pulse potential supply means;

a third transistor having its source electrode connected to said means for connection to said pulse potential supply means, its drain electrode connected to the source electrode of a seventh transistor and its gate electrode connected through said fifth transistor to first input terminal means;

15 the gate electrode of said third transistor connected through capacitance means to means for connection to a reference ground potential point; the drain electrode of said first transistor connected through first load means to means for connection to a drain-potential supply rail and the drain electrode of said second transistor connected through second load means to means for connection to said drain-potential supply rail the source electrodes of said first and second transistors connected to means for connection to a reference ground potential point;

20 a fourth transistor connected in parallel with said second transistor across the source and drain electrodes thereof, said fourth transistor having its gate electrode connected to second input terminal means and capacitance means connected between the gate electrode of said fourth transistor and means for connection to a reference ground potential point;

25 the drain electrode of said first transistor connected to the drain electrode of said seventh transistor and the drain electrode of said second transistor connected to output terminal means.

30 35 40 45 50 55 60 65 12. The ring-counter of claim 11 wherein said ring-counter contains "n" said elements — "n" being an integer greater than 2 — said output terminal means of each one of said elements being connected via feed-back paths to said second input terminal means of each of the (n-2) consecutive elements immediately preceding said one element.

13. The ring-counter of claim 12 wherein said first and second load means comprise eighth and ninth field-effect load transistors, respectively.

14. The ring-counter of claim 12 in integrated circuit form wherein said capacitance means comprise the gate to substrate capacitances of said third, fourth and seventh transistors.

15. The ring-counter of claim 12 wherein said capacitance means comprise the gate to substrate capacitances of said third, fourth and seventh transistors and each of said first and second load means comprises a field-effect load transistor.

16. The ring-counter of claim 11 wherein said first and second load means comprise eighth and ninth field-effect load transistors, respectively.

17. The ring-counter of claim 11 in integrated circuit form wherein said capacitance means comprise the gate to substrate capacitances of said third, fourth and seventh transistors.

18. The ring-counter of claim 11 wherein said capacitance means comprise the gate to substrate capacitances of said third, fourth and seventh transistors and each of said first and second load means comprises a field-effect load transistor.

19. The ring-counter of claim 11 wherein the input terminal means upon each said element for receiving a plurality of feed-back paths as aforesaid is connected to said feed-back paths through an OR-gate means, the output of said OR-gate means connected to said input terminal means and the inputs to said OR-gate means connected to said feed-back paths.

20. A ring-counter comprising a plurality of serially connected elements, each element having first and second data input terminal means and a data output terminal means, said data output terminal means of each element connected to one data input terminal means of the succeeding element to form a feed-forward path and said output terminal means of each element further connected to the second data input terminal means of the preceding element to form a feed-back path, each said element having tenth and eleventh cross-coupled field-effect transistors, the drain electrode of said tenth transistor connected through a thirteenth transistor to the gate electrode of said eleventh transistor, and the drain electrode of said eleventh transistor connected through a twelfth transistor to the gate electrode of said tenth transistor;

25 the gate electrode of said twelfth transistor connected to the source electrode of said tenth transistor and to means for connection to a first pulse-potential supply means;

30 the gate electrode of said thirteenth transistor connected to the source electrode of said eleventh transistor and to means for connection to a second pulse-potential supply means;

35 said first and second pulse-potential supply means giving first and second non-overlapping pulse trains, respectively, swinging between enabling pulses for the transistors in said element to which they are applied and disabling pulses therefor, these being periods of time between consecutive first and second and second and first pulses during which both said pulse-potential supply means give disabling potentials;

40 45 50 55 60 65 14. The ring-counter of claim 12 in integrated circuit form wherein said capacitance means comprise the gate to substrate capacitances of said third, fourth and seventh transistors and connected across the drain and source electrodes thereof, said drain electrodes of said tenth and fourteenth transistors being interconnected and connected through first load means to means for connection to said first pulse-potential supply means;

15 a sixteenth transistor in parallel with said eleventh transistor and connected across the drain and source electrodes thereof, said drain electrodes of said eleventh and sixteenth transistors being interconnected and connected through a second load means to means for connection to said second pulse-potential supply means;

16 first and second input terminal means, said first input terminal means connected to the gate electrode of said fourteenth transistor through a fifteenth transistor and said second input terminal means con-

connected to the gate electrode of said sixteenth transistor through a seventeenth transistor; the gate electrode of said fifteenth transistor connected to means for connection to said first pulse-potential supply means and the gate electrode of said seventeenth transistor connected to means for connection to said first pulse-potential supply means; capacitance means respectively connected between the gate electrodes of said tenth, eleventh, fourteenth and sixteenth transistors and means for connection to a reference ground potential point; output terminal means connected to the drain electrode of said sixteenth transistor; said output terminal means of each said element being connected to said second input terminal means of the preceding said element in said ring-counter and also connected to said first input terminal means of the succeeding said element in said ring-counter.

21. The ring-counter of claim 20 wherein said ring-counter contains "n" said elements — "n" being an integer greater than 2 — said output terminal means of each one of said elements being connected to said second input terminal means of each of the $(n-2)$ consecutive elements immediately preceding said one element.

22. The ring-counter of claim 21 wherein said first and second load means comprise eighteenth and nineteenth field-effect load transistors, respectively.

23. The ring-counter of claim 21 in integrated circuit form wherein said capacitance means respectively

comprise the gate to substrate capacitances of said tenth, eleventh, fourteenth and sixteenth transistors.

24. The ring-counter of claim 20 in integrated circuit form wherein said capacitance means respectively comprise the gate to substrate capacitances of said tenth, eleventh, fourteenth and sixteenth transistors and said first and second load means comprise eighteenth and nineteenth field-effect load transistors, respectively.

25. The ring-counter of claim 21 wherein the input terminal means upon each said element for receiving a plurality of feed-back paths as aforesaid is connected to said feed-back paths as aforesaid is connected to said feed-back paths through an OR-gate means, the output of said OR-gate means connected to said input terminal means and the inputs to said OR-gate means connected to said feed-back paths.

26. The ring-counter of claim 20 wherein said first and second load means comprise eighteenth and nineteenth field-effect load transistors, respectively.

27. The ring-counter of claim 20 in integrated circuit form wherein said capacitance means respectively comprise the gate to substrate capacitances of said tenth, eleventh, fourteenth and sixteenth transistors.

28. The ring-counter of claim 20 in integrated circuit form wherein said capacitance means respectively comprise the gate to substrate capacitances of said tenth, eleventh, fourteenth and sixteenth transistors of said first and second load means comprise eighteenth and nineteenth field-effect load transistors, respectively.
